UNITED STATES PATENT OFFICE.

JAMES VRBA, OF MARSHALLTOWN, IOWA.

WATER FRONT FOR FURNACES.

Application filed August 4, 1926. Serial No. 127,162.

In modern furnaces for house heating purposes there is sometimes provided at the furnace front at about the level of the grates a hollow water chamber communicating with 5 the water intake and outlet pipes, and so arranged that the heat within the furnace will heat the water desirable for household use. These water fronts are usually fixed in position and have their inner faces substantially flat vertically and curved horizontally to conform with the contour of the fire box, and flat at the top and bottom. With such arrangement in some instances, the water is heated excessively, which is objectionable, and in other instances it is not heated sufficiently. Furthermore, said water fronts frequently become cracked or broken due to the excessive heat and to the unequal contraction and expansion of said water 20 fronts.

The objects of my invention are to provide a water front for furnaces of simple, durable and inexpensive construction which may be formed of cast metal, and which, 25 on account of its shape, may be moved inwardly toward the combustion chamber or outwardly away from it, for the purpose of applying the desired amount of heat to the water under all conditions, and without impairing the efficiency or durability of either the water front on the furnace when the water front is located in any of its adjusted positions.

A further object is to provide a front of 35 this character so shaped and designed that the possibility of breakage, due to the contraction and expansion caused by excessive heat, is reduced to a minimum.

A further object is to provide improved 40 means for adjustably supporting the water front within the furnace.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a front elevation of a portion 50 of a furnace with parts broken away to show my improved water front in position.

Figure 2 shows a sectional view on the line 2-2 of Figure 1.

Figure 3 shows an enlarged sectional view

of the water front taken on the line 3-3 of Figure 1.

Figure 4 shows a vertical sectional view taken on the line 4-4 of Figure 2.

Figure 5 shows an enlarged sectional view 60 of the water front taken on the line 5-5 of Figure 1.

Figure 6 shows a front elevation of the water front and its adjustable supporting device; and

Figure 7 shows a sectional view of the same on the line 7-7 of Figure 6.

Referring to the accompanying drawings, I have used the reference numeral 10 to indicate generally the furnace, 12 indicates 70 the furnace grate and 13 the horizontal plate extending from the grate forwardly at substantially the grate level. Within the furnace there is a fire brick lining 14 of ordinary construction, terminating at the 75 sides of the plate 13.

My improved water front comprises a body portion cast complete in one piece. Viewed from the top it is of segmental shape and conforms substantially with the contour 80 of the inner surface of the fire brick lining, as indicated in Figure 2. Its inner face is curved, as shown in Figure 5, from a horizontal central line upwardly and outwardly at 15 and downwardly and outwardly at 16. 85 Its top is rounded at 17 and its bottom portion is also rounded as shown at 18 in Figure 5, and its front face is substantially flat as shown at 19. Projecting downwardly from the body of the water front is a rib 20 90 for the purposes hereinafter made clear. At one end of the water front there is a forwardly projected portion 21 with screw threaded pipe openings 22 therein, and pipes 23 and 24 are screwed into said openings. 95

At the horizontal central portion of the water front body is an integral partition 25 extended from the wall at the end where the openings 22 are formed to a point spaced apart from the other end, as shown in Figure 100 4, so that cold water coming in through the pipe 24 will travel horizontally the full length of the water front until past the partition 25, and will then rise and travel horizontally back again and flow out through 105 the upper pipe 23.

For supporting the water front, I have provided a base member comprising a cast body portion 26 of segmental shape as viewed from the top, and having projected 110

upwardly from its top edge a rib 27 which extends to a point spaced apart from the ends, and at each end is an upwardly projecting lug 28 spaced rearwardly from the rib 27. Said parts are so arranged that the downwardly extended rib 20 of the water front will stand between the rib 27 and the lugs 28, thus preventing forward and rearward movement of the water front relative to its supporting base, and providing a supporting base whereby the water front and base may be jointly moved forwardly and rearwardly upon the plate 13. In this connection, attention is called to the fact that this supporting base, when in use, stands spaced forwardly from the rear horizontal central portion of the water front, as clearly shown in Figure 5.

In practical use, attention is called to the fact that the water front body may be cast complete in a single piece. In applying the device to a furnace, the operator first rests the base 26 upon the plate 13 and then places the water front upon its supporting base. He then inserts the pipes 23 and 24 in the water front. Then the entire water front, together with its supporting base and water pipes, may be readily and easily moved and adjusted toward and from the center of the combustion chamber to suit the requirements of each particular furnace installation, or after a furnace has been installed and it has been demonstrated that either too much or too little heat is applied to the water front, the water front may be moved inwardly or outwardly as desired to obtain the proper amount of heat applied to the water front. By having the horizontal central portion of the inner face of the water front projected inwardly beyond the upper and lower edges thereof, the device is particularly adapted to be projected to a considerable distance into the furnace without any disadvantageous results, because the fuel or ashes within the furnace cannot become lodged or accumulated against the top of the water front, as would be the case if the inner face of the water front were substantially vertical and the top horizontal.

Furthermore, there will be no accumulation of ashes against the lower inner face of the water front, because it is elevated above the grate by the base member 26, and when ashes are removed from the grate, they will also fall away from the lower edge of the water front, even though some ashes should be lodged against the inner face of the base member 26.

Hence, by means of my improved construction, the water front may, if desired, be projected into the furnace, without any disadvantageous results, to a greater extent than is possible with the forms of water fronts now in common use.

When it is determined that excessive heat

is being applied to the water front, then the operator simply moves the entire water front and supporting base forwardly in the furnace, and when this is done, and on account of the shape of the inner face of the water front, and its elevated position with relation to the grate on account of the base member 26, ashes and fuel will not become lodged against said inner face of the water front when the grates are kept reasonably clean.

I have demonstrated in actual practice that by forming a water front of the shape illustrated and described and without any square corners or ends, the unequal contraction and expansion, to which these devices are subjected to when in use, will not tend to break or crack the water front, such as is done in a large percentage of instances with water fronts of the type heretofore commonly used.

I claim as my invention:

1. A water front for furnaces, comprising a hollow body portion of substantially segmental shape as viewed from the top, and having its inner face curved so that adjacent to its horizontal center it projects inwardly toward the center of the furnace, and its upper and lower edges project outwardly away from the center of the furnace, means for connecting water circulating pipes to one end of said body portion, a flange extended downwardly from the lower edge of the body portion, and a base member designed to rest upon a suitable support and having a contour as viewed from the top corresponding to that of the body portion and having an upwardly extended rib and lugs to grip between them the downwardly extended flange of the body portion, and designed to support the body portion in position spaced above the support on which the base rests and to permit the rear portion of the body to project rearwardly beyond said base, for the purposes stated.

2. A water front device for furnaces of the class having a substantially flat horizontal water front supporting plate above the grate, comprising a hollow body portion of substantially segmental shape as viewed from the top, and having its inner face curved in such a manner that its horizontal center projects inwardly toward the center of the furnace and its lower surface projects downwardly and outwardly and its upper surface projects upwardly and outwardly, means for connecting water circulating pipes to one end thereof, a base member comprising a body portion shaped to be slidably supported upon the said furnace plate, means for detachably connecting the base to the water front body portion, the inner face of said base member being shaped to extend straight downwardly from the lower edge of the water front body to there-

by prevent the accumulation of ashes upon said plate and under the bottom of the water front, the said parts being so arranged that the water front and the base

5 may be freely moved inwardly and outwardly relative to the furnace to project greater or less distances into the furnace, and when

in any of its adjusted positions the base member will retain the same position relative to the water front, substantially as and 10 for the purposes stated.

Des Moines, Iowa, June 9, 1926.

JAMES VRBA.
